UNITED STATES PATENT OFFICE.

EDWARD HALL, OF WHITESTONE, NEW YORK, ASSIGNOR OF FORTY ONE-HUNDREDTHIS TO CHARLES F. PEACE AND JOHN R. TOWNSEND, OF WHITESTONE, NEW YORK.

TROLLEY.

SPECIFICATION forming part of Letters Patent No. 736,721, dated August 18, 1903.

Application filed May 28, 1903. Serial No. 159,071. (No model.)

To all whom it may concern:

Be it known that I, EDWARD HALL, a citizen of the United States, residing at Whitestone, in the county of Queens and State of New York, have invented certain new and useful Improvements in Trolleys, of which the following is a specification, such as will enable those skilled in the art to which it appertains to make and use the same.

10 The object of this invention is to provide a trolley for electric street or other railway cars to be used in connection with the so-called "overhead-wire" system and which is simple and durable in construction and which 15 will not allow the trolley-wheel to jump off the conductor-wire, but will retain the trolley-wheel and conductor-wire in operative connection at all times; and with this and other objects in view the invention consists in 20 a device of the class specified, constructed as hereinafter described and claimed.

The invention is fully disclosed in the following specification, of which the accompanying drawings form a part, in which the separate parts of my improvement are designated by suitable reference characters in each of the views, and in which—

Figure 1 is a side view of a trolley device constructed according to my invention and 30 showing also a part of an overhead wire or conductor; Fig. 2, a similar view of the trolley device, but showing the parts in a different position; Fig. 3, a sectional view looking in the direction of the arrow x of Fig. 2, and 35 Fig. 4 a section on the line 4-4 of Fig. 2.

In the practice of my invention I provide a yoke or fork a , having a socket a^2 , with which the usual trolley-arm b is connected, and the yoke or fork a is provided with two downwardly-directed arms a^3 , which are preferably at an angle of about forty-five degrees to the trolley-arm, but which may be at an acute angle, if desired. The arms a^3 of the yoke or fork a are provided with longitudinal spaces 40 a^4 , in which are mounted journal-boxes c , and at the opposite sides of the spaces a^4 are grooves a^5 , and the journal-boxes c are provided with side ribs or projections c^2 , which move in the grooves a^5 , and between the journal-boxes c and the bottom portions of the 45

arms a^3 are placed springs d . The longitudinal spaces a^4 in the arms a^3 open at the top of said arms in order that the journal-boxes c may be passed thereinto, and secured to the top portion of said arms are blocks e , which hold the journal-boxes in place and prevent their being thrown out by the springs d . 55

The trolley-wheel f is provided with a shaft f^2 , supported by the journal-boxes c , and said trolley-wheel is also preferably provided at 60 each side with a short hub f^3 , and these hubs bear on the journal-boxes c , and by reason of this construction there is a slight space between the trolley and the separate side members a^3 of the yoke or fork a . 65

Connected with the separate side members a^3 of the yoke or fork a and at a predetermined distance rearwardly of the journal-boxes c , as shown at g , are yoke-shaped arms h , preferably composed of heavy wire or small 70 rods, and the separate sides h^2 of the yoke-shaped arms h are connected with the parts a^3 of the fork or yoke a at both sides thereof, as clearly shown in Fig. 3, and in order to accomplish this result the separate side portions h^2 of the yoke-shaped arms h are bent 75 to form rings or eyes h^3 , through which the pivot pin or bolt g is passed, and each side portion h^2 of each of the yoke-shaped arms h is also formed into a projecting finger h^4 at 80 each side of the side members a^3 of the yoke or fork a , and these projecting fingers h^4 are passed through keepers h^5 at each side of the journal-boxes c . As thus constructed the arms h , which project backwardly and upwardly when the separate parts are in their normal position, as shown in Figs. 1 and 2, 85

will rise and fall with the journal-boxes c , and these journal-boxes will rise and fall according to the pressure applied by the trolley-wire or conductor j , and when the journal-boxes c are depressed the arms h will be depressed, as shown in full lines in Fig. 1, and when said journal-boxes rise the arms h will be thrown up, as shown in dotted lines in 90 Fig. 1, and this movement of the arms h will prevent the trolley-wheel from jumping the wire j or prevent said wire from jumping off of the trolley-wheel. It is well known that 95 the trolley and wire conductor are frequently 100

disconnected by reason of violent movements of the trolley-arm *b*, caused by the motion of the car, and this necessitates the readjustment of the trolley-wheel and the placing 5 thereof in connection with the wire or conductor *j*; but by means of my improvement the wire conductor *j* is prevented from leaving the trolley-wheel, the arms *h* serving at 10 all times to hold said wire or conductor in proper and operative position with relation to the trolley-wheel *f*.

It will be understood, of course, that the trolley-arm *b* is connected with a car in the usual manner and is adapted to swing both 15 in a horizontal and vertical direction, the vertical movement thereof being regulated by a spring; but these parts form no part of this invention, and therefore are not shown and described.

20 Having fully described my invention, what I claim as new, and desire to secure by Letters Patent, is—

1. A trolley device, comprising a fork having downwardly-directed arms, vertically-25 movable and spring-supported journal-boxes mounted in said arms and by which the trolley-wheel is supported, and yoke-shaped side arms pivoted to the fork rearwardly of the journal-boxes and extending upwardly and

backwardly, and the separate side members 30 of which are provided at their pivotal supports with backwardly-directed fingers which pass through keepers secured to the journal-boxes whereby said arms are given a vertical movement by the rise and fall of the journal- 35 boxes, substantially as shown and described.

2. A trolley device comprising a fork having downwardly-directed arms, vertically-movable and spring-supported journal-boxes mounted in said arms and in which the trolley-wheel is supported, and guard-arms pivoted to the side members of the fork and projecting upwardly and backwardly and provided at their pivotal supports with backwardly-directed members in operative connection with the journal-boxes whereby said guard-arms are raised and lowered by the movement of the journal-boxes, substantially 45 as shown and described.

In testimony that I claim the foregoing as my invention I have signed my name, in presence of the subscribing witnesses, this 26th day of May, 1903.

EDWARD HALL.
